Specification of Letters Patent. Patented Apr. 24, 1917.

Application filed August 20, 1915. Serial No. 46,510.

To all whom it may concern:

Be it known that I, WILLIAM A. WEBSTER, a citizen of the United States, and a resident of Galesburg, in the county of Knox and 5 State of Illinois, have invented a new and useful Sack-Baler, of which the following is a specification.

My improvements relate more particularly to devices for baling cement, salt and other 10 sacks with wire and for securing the ends of the bale-wire together after the bale is completed. However, it will be evident, as the nature of the invention is further disclosed and better understood, that the improvements 15 are of such nature that they may be employed with equal success for baling and tying bundles of angle and other irons, ax, fork and other handles, and for other purposes too numerous to specifically enumerate. 20 The present invention is purposed and designed as an improvement on the machine disclosed in Letters Patent granted to me April 13, 1915, No. 1,135,931, and the improvements are directed mainly toward the 25 provision of pivoted levers which constitute a part of the frame, said levers adapted for purposes presently more fully described; toward the provision of packer-arms or forks; toward the means for temporarily holding 30 the wire in order that it may sustain the sacks before they are compacted; toward the provision of a frame especially adapted to coact with the means above recited and with the means next recited; toward the provision 35 of specially constructed wire-tying devices, whereby they will not become disassembled when the above noted pivoted levers are reversed from their normal positions; toward other novel features included in the tying 40 devices; and toward minor novel features hereinafter described.

The objects of the invention are, therefore, to generally improve the construction and to increase the capacity, utility and efficiency 45 of devices of this character.

By way of example a baling press embodying the features of the invention is illustrated in the accompanying drawings, in which:

50 Figure 1 is a perspective, a quantity of sacks being sustained, by the baling wires, in position for compression and for tying.

Fig. 2, a detail side elevation of the wire-tightening and twisting lever or crank;

Fig. 3, a bottom plan of a wire-twisting 55 disk;

Fig. 4, a bottom plan of the element shown in Fig. 2;

Fig. 5, an end detail of the wire-twisting 60 disk;

Fig. 6, an edge view thereof;

Fig. 7, a fragmental section, taken in the plane of the line 7—7 in Figs. 3 and 4, but turned end-for-end;

Fig. 8, a modification of the frame-locking 65 insert shown in Figs. 10 and 11;

Fig. 9, a top plan, the supporting arches and delivery table not shown;

Fig. 10, a detail elevation of the frame-locking insert shown in Fig. 1; 70

Fig. 11, an edge elevation thereof;

Fig. 12, a detail of the wire-clamp;

Fig. 13, an end elevation (relatively to the frame) of one of the hinge-butts;

Fig. 14, an end elevation of one of the 75 pivoted-frame-levers, also considered relatively to the frame;

Fig. 15, a top plan of one of the hinge-butts;

Fig. 16, a bottom plan of the lever shown 80 in Fig. 14;

Fig. 17, a top-plan of one of the packer-arms;

Fig. 18, an edge view thereof; and

Fig. 19, a perspective—a modification of 85 the frame-locking insert.

Considering the drawings in detail and referring to the elements and, where necessary, to the parts thereof, each by a distinguishing character, uniformly employed, 90 2—2 designate supporting arches of channel-iron. 3—3 designate cross-bars, the bent ends of each of which are secured to the legs of the arches 2 as presently more fully described. 4—4 designate channel-iron struts. 95 5—5 (Figs. 10 and 11) designate frame-bar-locking inserts, comprising each a longitudinally arranged arm or branch 6 and a transversely arranged arm or branch 7, said arms lying in different horizontal planes and each insert provided with an aperture 5a passing through both branches. The arm 6 rests in the channel of the strut and the arm 7 in that of the arch, and a bolt or rivet 8

100

is passed through the strut, the insert, the leg of the arch, and the cross-bar, to hold them rigidly together, as is essential in this class of devices. In Fig. 8 I have shown a modified form of insert, 5', to be used when the channel of the strut is faced outward. The arm 6' would then lie in the channel of the arch, and the recess 7' would receive and rigidly hold the strut from movement 5 relatively thereto. In Fig. 10 I have shown another modified form of insert 5'', this one purposed for use when the strut runs at another angle than a right one relatively to the arch. 9, 9' indicate the longitudinal, and 10, 10 the transverse bars of a sack-receiving and delivering table, the bars 9, 9' being secured to the arches 2 and the bars 10, 10 to the bars 9, 9'.

11, 11' designate hinge-butts secured in 20 acting pairs on the forward and rear corners respectively of the arches and provided each with a forked end having eyes 12. 13, 13' indicate frame-levers having each an eye 14, a foot 15 and a tongue 16. 17, 17 designate 25 bolts passed through the eyes in the pairs of hinge-butts and levers, and they serve as pivots for the latter. 18 designates a pivoted frame-bar secured at 19 to the swinging ends of the levers 13, and 20 designates a 30 similar bar secured to the levers 13'.

21, 21 designate packer-forks fixed each by a bolt 23 passed through the eye 22 thereof, to the frame-bar 20, the tongue 24 extending over an edge and the inclined portion 25 resting on the plane lower face of said bar whereby to incline each fork normally downward.

26 indicates the stationary disk member of the wire-twisting or tying means and comprises a base having a radially arranged mouth 28 extending in rear of its axis, a peripheral groove 29, and a projection 30 having an aperture 31 for the reception of suitable means for securing it to the bar 18. 40 Of these disk members, and of the parts co-operating therewith and now to be described there may be any suitable number. 32 designates a twisting-head or hub having a crank-handle 33, its bottom provided with a 45 radially cut slot 34 terminating in a flared mouth 35 which cuts also the rim 36. Said bottom and rim form a socket rotatable on the disk 26. 37 indicates a set screw threaded through an aperture in said flange, its 50 point extending into the groove 29.

To assemble the wire-tying members the mouth 28 is positioned over said screw-point and the disk then dropped into place in the socket. Upon it being rotated the screw-point 60 will enter the groove 29 and prevent the element 32 from dropping off the disk 26, when the frames are swung to the reversed positions shown in Fig. 9. 38 indicates a wire-holding pin fixed in the member 65 32.

For initial securement of one end of the wire I have provided the means shown best in Fig. 12, one set of these means co-operating with each tying mechanism. 39 designates a crank-screw onto which a nut 40 70 is tightly threaded. The stem of said screw is then passed loosely through an aperture 41 in the vertical arm of the bar 20 and its end portion engaged with the free end portion of a spring clamp-plate 42, the other end of said plate being secured by a bolt 43 and nut 44 to said arm and spaced therefrom by a washer 45.

To operate the device the pivoted frames are swung to the horizontal open positions 80 shown in Fig. 9, in which positions they will be maintained because of the shoulders 46 (Fig. 16) of the frame-levers coming up against the ends 47 (Fig. 15) of the hinge-butts. One end of each baling-wire 48 is 85 then placed between the bar 20 and spring 42 (see Fig. 12) and the screw 39 given a part rotation to draw on said spring and thereby clamp the wire. The other end of each wire is then passed through the mouths 90 of the tying elements and wrapped around the pin 38. The sacks 49 are then laid one upon another on said wires, and when a sufficient number has been thus piled the pivoted frame 50 is swung to the position 95 shown in Fig. 1, the frame 51 meanwhile being swung on its pivot but its throw not completed until after the frame 50 has reached its final position of rest. (These movements may of course be slightly deviated from.) As the packer forks 21 were 100 swung they pressed over and held down the edges of the sacks, compacting them into proper bale-form, the wires meanwhile closing around and forming loops on the bales 105 and drawing the sacks into positions for tying. The operator then twists around the pin 38 the projecting end of that portion of the wire held by the clamp 42, thus bringing it through the mouths of the coacting tying 110 elements and into the slot 34, and then rotates the handle 33 clockwise, the adjacent wall of the mouth 35 striking the wire and 115 freeing it from said clamp. Continued rotations of the element 32—33 will, by twisting the wire ends about each other as shown in Fig. 7, shorten the loop and cause it to tightly bind and compress the bale of sacks.

When the tying operation has been completed the wires are released and the bales 120 will fall onto the inclined delivery table 9—10 from whence they will roll onto the floor at the front side of the machine, where they may be readily handled.

The feet 15 rest, when in normal positions, each in the channel of one of the supporting arches 2, whereby the bars 18 and 20 and thereby the tying and packing means are supported.

I have shown and described that embodi- 130

ment of my invention which is at present preferred by me, since it has in practice been found to give gratifying results, but have not deemed it necessary to encumber 5 the specification and drawings with descriptions and illustrations of modifications which are neither essential to nor form any part of the invention, considered in its broadest aspect. In fact, it will be quite evident that 10 numerous structural changes may be made, and that some of the parts may be used without the others and without departing from the spirit and scope of the invention. Therefore, without limiting myself to particularities except in those places in which 15 they are specifically recited, I claim as new the following to-wit:

1. In a baler, a supporting frame, frames pivotally connected therewith and adapted 20 to swing toward and from each other, wire-tying means carried by one of said swinging frames, and wire-end-holding means carried by the other thereof.

2. In a baler, a supporting-frame, frames pivotally connected therewith, wire-end-se- 25 curing elements, swinging one with each of the last recited frames and each thereof adapted to hold one end of a baling-wire, and means for tying the ends of the wires.

3. In a baler, swinging frames, a wire- 30 end-holding device carried by one of them, and means carried by the other and adapted to free the wire from said holding-device.

4. In a baler, swinging frames, a wire- 35 end-holding device carried by one of them, and wire-tying members carried by the other, one of said members adapted to free the wire from said device.

5. In a baler, swinging frames, a friction- 40 clamp carried by one of them, and means carried by the other and adapted to free the wire from said clamp.

6. In a baler, a frame adapted to be swung 45 to reversed position, plural member wire-ty- ing means carried thereby, and means for preventing said plural members from be- 50 coming disassembled when the frame is re- versed.

7. In a baler, a supporting-frame, swing- 55 ing frames, one hinged at each side thereof, a wire-clamp carried by one of said swing- ing frames, and wire-tying means carried by the other.

8. In a baler, oppositely-swinging frames, 55 a wire-clamp carried by one of them, wire-

tying mechanism carried by the other, and wire-end engaging means carried by said tying mechanism.

9. In a baler, a supporting-frame, swing- 60 ing frames carried thereby, wire-tying means carried by one of said swinging frames, and packer-arms carried by one of said swinging frames.

10. In a baler, a reversible frame, a wire-tying disk secured thereto and provided 65 with a peripheral groove, a wire-tying mem- ber coöperating with said disk and having an aperture in its side, and means engaging said aperture and adapted to lie partly within said groove, whereby when the frame 70 is reversed the parts comprising the tying mechanism will not become disassembled.

11. In a baler, a reversible frame, and wire-tying elements carried thereby and re- 75 versible therewith, one of said elements ro- tatable on the other.

12. In a baler, a pair of oppositely-swing- 80 ing frames, a clamp-plate carried by one of them, means for adjusting it relatively to the frame which carries it, whereby to pro- vide a clamp for one end of a baling-wire, means for holding the other end of the wire, and means for uniting said ends.

13. In a baler, swinging frames, means 85 carried by one of them for insecurely hold- ing one end of the wire, means carried by another of said frames for holding the other end of the wire, packer arms carried by one of said frames, and wire-tying means car- ried by one of said frames. 90

14. In a baler, a pair of arches, struts connecting them, hinge-butts secured one to each upper corner of each arch to form pairs, rods, one connecting each pair of butts, frames pivoted one on each rod, and 95 wire-tying means carried by one of said frames.

15. In a baler, a pair of arches, means for connecting them whereby to form a sup- 100 porting frame, hinge-butts secured one to each corner of said frame, whereby to form oppositely disposed pairs, rods, one connect- ing each of said pairs, frames pivoted one on each rod, wire-tying devices carried by one of said frames, and packing-elements 105 carried by one of said frames.

In testimony whereof I hereto affix my signature this sixteenth day of August, 1915.

WILLIAM A. WEBSTER.
